PROCESS FOR THE PRODUCTION OF MAGNESIUM BY MEANS OF THERMIC REDUCTION

Luigi Amati, Padova, Italy

Application January 26, 1940, Serial No. 315,849
In Italy July 1, 1939

1 Claim. (CL 75—67)

The present invention relates to a process for the production of magnesium by thermic reduction, under vacuum or reduced pressure, of magnesium-containing raw materials, by means of reducers such as silicon, ferro-silicon, aluminum or similar reducing substances which do not generate gaseous products of oxidation.

As is well known, various difficulties are encountered in the production of magnesium by thermic reduction which make it impossible to carry out such a process in continuous manner on an industrial scale. The art has therefore resorted to intermittent processes comprising the following cycle of operations: charge of the material to be treated, heating of the material, distillation, condensation, and discharge of the resultant magnesium and of the exhausted residual material.

The magnesium distilling from the reaction zone is condensed in a suitable zone at a temperature of about 500°. In order to extract the magnesium from this zone, it is necessary to wait until it cools to a temperature below 80-100° C., since otherwise the magnesium would react with the atmospheric air and be covered by a layer of nitride and oxide of greater or less thickness, thereby greatly reducing the yield of metallic magnesium. The reaction with the air may be so violent that the magnesium may be set on fire and be totally converted into oxide.

In practice, the condensation zone is externally cooled, and this cooling has to be continued even after the reduction reaction has been completed. However, this procedure, the object of which is to shorten the duration of the period of cooling of the condensed magnesium, also incidentally cools the reaction chamber. This results in a considerable loss of heat so that large additional quantities of heat have to be supplied during subsequent reduction operations, thereby unfavorably affecting the heat consumption.

The process of the present invention makes it possible to obviate, in simple manner, the above-enumerated defects and disadvantages, and to reduce thermic losses and the time required for carrying out the whole operative cycle to a minimum. The present process is characterized by the fact that the magnesium produced by the thermic reduction is extracted in a condensation which is under a degree of vacuum substantially corresponding to the degree of vacuum prevailing in the reduction chamber, the condensation chamber being subsequently made entirely independent of the reduction chamber. The conse-

quence of this arrangement is that, as soon as the thermic reduction has been completed, the apparatus may at once be used for a new operation, as hereinafter explained.

- 5 The aforesaid process may be carried out with the aid of the apparatus hereinafter described and illustrated, solely by way of example, in the single figure on the accompanying sheet of drawing.
- 10 The said figure of drawing is a diagrammatic longitudinal sectional view of the aforesaid apparatus, and reference character 1 represents an electric furnace, 2 a heating coil, 3 a reaction chamber, 4 a receptacle containing the reaction mass, 5 a condenser for the resultant magnesium, 6 a closure device for the condenser 5, 7 means for controlling the closure device 6, 8 a cover for closing the outer end of the condenser 5 and the reaction chamber 3, and 9 a valved conduit leading to a vacuum-producing means (not shown).

The procedure according to the present invention is as follows:

- 25 The raw material, intimately mixed with the reducer and generally briquetted, is charged into the receptacle 4 and introduced into the reaction chamber 3 where it is heated under vacuum or at a reduced pressure at a temperature depending upon the type of reducer employed.
- 30 The evolved magnesium is condensed in condenser 5. As soon as the reaction ends, the closing device 6 is actuated by lever 7, cutting off communication between the condenser 5 and the reaction chamber 3. Then the wing nuts which
- 35 affix the cover 8 to the reaction chamber are unscrewed and the condenser 5 is removed, the magnesium contained therein undergoing no chemical alteration notwithstanding the fact that it is at a high temperature. The reaction chamber, after removal therefrom of the receptacle 4, may immediately be utilized again for a new operation by filling it with a new charge and positioning a new condenser therein.

- 40 45 As is clearly evident, the advantages inherent in the present process and apparatus affect time and thermic output.

As a matter of fact, the possibility of quickly removing the condenser 5 and thus permitting the immediate re-utilization of the apparatus, results in an appreciable reduction in the time of interruption of the productive cycle. Moreover, the removal of the condenser containing the magnesium, according to the aforescribed method, makes it possible to avoid supplementary

cooling which, as above stated, is indispensable according to prior processes. The result is that, while according to the prior processes the reaction chamber is cooled with the aid of a cooler annexed to the condensation zone, this is avoided according to the present invention and, consequently, there is a substantial reduction in the quantity of heat which has to be supplied to the apparatus for subsequent thermic reduction operations. In addition, no heat is lost as a result of long delays during which the apparatus has to remain inactive, waiting for the magnesium produced therein to reach such a temperature that it may be removed with no danger whatsoever of oxidation.

I claim:

A process for the production of magnesium by thermic reduction in a reduction zone at reduced pressure, which comprises condensing the

5 evolved magnesium in a condensation zone juxtaposed to and in communication with said reduction zone at a pressure substantially equal to that prevailing in the reduction zone, cutting off the communication between the reduction zone and condensation zone while maintaining the juxtaposition thereof, whereby the atmosphere and pressure prevailing in the condensation zone are rendered independent of the atmosphere and pressure prevailing in the reduction zone without change in such pressure, and dissociating the condensation zone from said reduction zone whereby the latter may immediately be reassociated with a new condensation zone, the pressure prevailing in the condensation zone after 10 said dissociation being substantially the same as that prevailing in the system during the reduction process.
